PIPETTE

Jules Barry Cohen, Brooklyn, N.Y., assignor to Medical Laboratory Automation, Inc.

Filed June 17, 1971, Ser. No. 154,262

Term of patent 14 years

Int. Cl. D24—02
U.S. Cl. D16—2 C

FIG. 1

FIG. 2

FIG. 4

FIG. 5

FIG. 1 is a perspective view of a pipette embodying my new design;

FIG. 2 is an end view of the pipette looking from the tip thereof;

FIG. 3 is a front elevational view of the pipette;

FIG. 4 is a side elevational view of the pipette; and

FIG. 5 is a top plan view of the pipette.

I claim:

The ornamental design for a pipette, as shown.
